SAFETY DRILLING-IN HEAD

Ferdinand J. Spang, Butler, Pa., and Ray B.
Anderson, Charleston, W. Va.

Application June 20, 1939, Serial No. 280,090

14 Claims. (Cl. 166—15)

This invention relates to the drilling of oil and gas wells by the cable tool method and for its broad object the production of an improved safety drilling-in head by means of which the flow of oil and gas from a well during drilling can be kept under control and diverted from the working areas.

In drilling oil and gas wells by the cable tool method, a string of casing is set in the hole that has been previously drilled. A string of cable tools consisting of a drilling bit, sinker bar, jar and rope socket suspended from the end of a drilling cable is lowered into the casing and vertically reciprocated by means of a walking beam, the outer or free end of which is located above the upper end of the casing. Drilling continues until oil or gas is encountered in sufficient quantity.

When oil or gas is encountered in sufficient quantity it flows upward and out of the upper end of the casing; sometimes to a considerable height. This flow entails great danger from fire or explosion, and, in order to eliminate this danger, it is the practice to equip the upper or open end of the casing with a casing head and to attach to this a so-called oil and gas saver. Such oil and gas savers in general are provided with a central aperture for the drilling cable. This aperture is surrounded by packing through which the drilling cable moves. By this means an attempt is made to prevent leakage of oil and gas around the drilling cable.

With these prior devices when it is necessary to withdraw the string of drilling tools from the hole, the oil saver must first be disconnected from the casing head and this in itself is a dangerous operation due to the fact that the oil and gas pressure often blows the device upward with considerable velocity. Even after the device is disconnected from the casing head, it still remains on the drilling cable.

Some oil and gas savers have been devised which are automatically disconnected from the casing head but these are all more or less complicated and all have the main disadvantage of the older type in that they also remain on the drilling cable when disconnected from the casing head.

After the oil or gas saver has been disconnected from the casing head (either automatically or manually) the string of tools is withdrawn from the hole and during this procedure the oil and/or gas passes freely into the work area and is likely to cause considerable danger from fire

or explosion and of course is detrimental to the health of the workmen.

While as stated above, various devices which attempt to overcome this difficulty have been devised and a number have been patented, none have proved entirely satisfactory and another object of this invention is to produce a device for packing a drilling cable and which is so constructed as to open automatically to permit a string of drilling tools to freely pass therethrough.

A still further object is to produce a drilling cable packing device which is adapted to be opened by upward movement of the rope socket and which when so opened, allows free passage therethrough of the rope socket and drilling tools.

A further object of this invention is to produce an oil and gas saver which without being disconnected from the casing head will open automatically and permit the passage of a string of drilling tools therethrough.

A further object is to produce a packing device for a drilling cable that may be so adjusted from time to time as to compensate for wear occasioned by the drilling cable.

A still further object is to produce a safety drilling-in head having in its make-up cable guide spools or rollers and means for varying the spacing of such spools or rollers to accommodate drilling cables of different sizes.

Another object is to produce an organized apparatus comprising a safety drilling-in head which in its make-up includes a drilling cable packing means which is opened automatically to allow passage therethrough of the string of drilling tools; packing means for the string of drilling tools which prevents upflow of oil and gas when said tools are passing therethrough, means for shutting off the flow of oil or gas when the string of tools has cleared its packing means and means for diverting the oil and gas from the working areas.

A still further object is to produce a safety drilling-in head which in its make-up includes a drilling cable packer which is adapted to be opened automatically to permit the free passage therethrough of drilling tools; a packer for such drilling tools which functions while the cable tool packer is open; a shut-off gate valve which can be closed prior to the time the drilling-in string has been completely pulled above the device and a diversion chamber which functions to divert the flow of oil and gas from the working areas

when the drilling cable packer is open as well as when the same is closed.

These and other objects which will readily appear to those skilled in this particular art, we attain by means of the safety drilling-in head described in the specification and illustrated in the drawings accompanying and forming part of this application and in which:

Fig. 1 is a view in sectional elevation of a safety drilling-in head embodying this invention. In this view, the cable packing means or device is shown in closed position and the single disk shut-off gate valve is also shown in closed position.

Fig. 2 is a view of the cable packing device in open position; parts being shown in section and parts in elevation.

Fig. 3 is a perspective view of the cable packing device, and in this view one-half of the device is shown in closed position with the other half in open position;

Fig. 4 is a detail view of one of the hinged portions constituting one-half of the drilling cable packing device;

Fig. 5 is a transverse sectional view taken through the center of the cable packing device when in closed position;

Fig. 6 is a perspective view of one of the four flexible annular members entering into the make-up of the drilling tool packing portion of the safety drilling-in head;

Fig. 7 is a perspective view of the flexible annular member which serves to seal the water courses of the drilling bit as well as other irregular surfaces of the drilling-in tools constituting the string;

Fig. 8 is a perspective view of the single disk shut-off gate valve and the means for raising and lowering the valve as it is moved toward and from its seat;

Fig. 9 is a detail sectional view of the valve disk and its seat;

Fig. 10 is a longitudinal sectional view of one of the roller or spool mounting pins; and

Fig. 11 is an end view of such pin looking toward the right of Fig. 10.

The safety drilling-in head of this invention as disclosed herein and particularly in Figure 1 of the drawings comprises a diversion chamber, a shut-off gate valve, a packing device for the string of drilling tools and a packing device for the drilling

in head. The diversion chamber is indicated by A; the shut-off gate valve assembly by B; the packing device for the string of drilling tools by C and the packing device for the drilling

in head by D.

The drilling-in head is adapted to be attached to the top of the master gate which is mounted on the upper end of the casing head. The diversion chamber 20 is provided with a bottom opening 21 surrounded by a flange 22 by means of which the device is attached to the top of the master gate. The diversion chamber is preferably provided with one or more side openings 23 (one only being shown) which are threaded to receive flow pipes for leading the oil and gas away from the drilling rig. Chamber 20 at its top is provided with an outwardly extending annular flange 24.

A housing having a bottom member or floor portion 25 and a top member or portion 26 and which is adapted to house a sliding gate valve member or disk 27, is secured to the top of the diversion chamber by means of an annular retaining member 28 which underlies annular

flange 24 at the top of the diversion chamber and which is secured to bottom member 25 by a suitable annular series of bolts 29.

Seat 30 for the valve member or disk is formed at the top of an annular member 31 and this member is provided with an outwardly extending flange 32 which underlies that portion 33 of bottom member 25 of the valve housing which surrounds valve seat member 31.

The inner peripheral surface of the diversion chamber adjacent its top is cut away, as best shown in Figure 9, to provide an annular shoulder 34 which serves as a support for the valve seat assembly. An annular member 35 which rests on said shoulder serves as a support for a flexible ring 36 preferably molded from soft rubber. Located between the top of ring 36 and the bottom face of valve seat member 31 is an annular metallic member 37 similar to member 35. Annular member 35 is provided with an upstanding annular ridge 38 and member 37 with a downwardly extending annular ridge 39. These ridges as disclosed in Fig. 9 press into flexible ring 36 and hold the same in place. Valve seat member 31 has its outer surface grooved as at 40 to receive an annular rubber ring-like member 41. Member 41 extends outwardly beyond the outer peripheral surface of member 31, and the upper surface of bottom member 25 of the valve housing is provided with a slight annular groove 42 within which the protruding portion of ring 41 seats.

From the foregoing, it will be seen that valve seat member 31 is yieldingly held in its normal or upper position in contact with the under face of bottom member 25 of the valve housing by flexible member 36 and because of said member 36 is permitted to yield downwardly. Flexible rubber ring 41 serves as a seal between the outer surface of member 31 and bottom member 25, of this valve housing.

The top or roof member 26 of the valve housing is provided with a circular opening 43 in axial alignment with the circular opening defined by the valve seat 30 and with opening 21 in the bottom of the diversion chamber.

The lower face of valve member 27, as best shown in Fig. 9, is flat so as to contact evenly with its seat 30. The upper surface of the valve member from a point 44 adjacent its end 45 tapers gradually to a point 46 adjacent its opposite end 47. Valve member 27 on opposite sides and extending inwardly from its side edges has its upper surface cut away to provide side portions 48 which are flat and which parallel the bottom surface of the valve; intermediate portions 49 which are relatively longer than portions 48 and which taper gradually from portions 48 to end portions 50 which proceed to edge 47 on a much steeper slope than portions 49.

Valve member or disk 27 is operated by a stem 51, one end of which is secured to the valve member by a suitable interlocking connection 52. Valve stem 51 projects outwardly beyond the valve housing or chamber through a suitable stuffing box 53.

Each side member 54 of the valve housing or chamber is provided with an inwardly extending bottom flange 55 which throughout the major portion of its length has an upper surface 56 which parallels the upper surface of the floor or bottom member 25 of the valve housing as well as the plane defined by valve seat 30. The end of flange 55 adjacent the valve seat tapers downwardly toward the valve seat as shown at 57 so

that the upper surface of this tapered portion at its end 58 is located slightly below the plane defined by the valve seat. Flanges 55 located as they are on opposite sides of the valve housing form support slides or rails upon which valve member 27 rests, when in open position, and upon which it slides toward and from closed position. From this construction, it will be seen that as soon as the valve member or disk 27 is moved toward open position or in other words, away from its seat, it rides up incline 57 and is raised from its seat.

In order to insure close contact between the lower face of the valve disk 27 and its seat 30, each side member 54 of the valve housing on opposite sides of the valve seat is provided with an inwardly extending flange portion 59 which at its inner end 60 overlaps end 58 of inclined portion 57 of the support rails or slides 55. The under face 61 of each of the flanges 59 is inclined downwardly from end 60 to a point immediately adjacent end 62 of the valve housing. These inclined faces 61 cooperate with surfaces 48, 49 and 50 on the sides of valve member 27 in forcing the valve into firm contact with its seat to prevent the upward flow of gas and oil after the drilling string has been pulled above this point.

The valve member or disk is moved to and from closed position by means of a lever 63 pivoted at 64 to a channel member 65 which is bolted to the derrick floor 66. Lever 63 at its upper end is provided with a weight member 67 and at its lower end, which extends through a slot in the derrick floor, it is connected to the outer end of valve stem 51 through a suitable connecting rod 68, 35 yokes 69 and a beam or lever 70. The lower end 71 of beam or lever 70, by means of a rod 72, is connected at 73 to a fulcrum bracket 74 which is secured to and depends from the valve housing. Member 67 is of such weight as to hold lever 63 in the position to which it is moved manually, regardless of vibrations that might otherwise cause it to shift its position. When the valve is moved to closed position, weight 67 will hold it in closed position and when the lever is shifted to open the valve, the valve will be held in open position until it is shifted by means of lever 63.

The drilling-in tool packing device C is contained within a tubular housing member 75 and comprises an annular water course sealing disk and a series of flexible annular disks serving as pressure reducing media and sealing disks for the drilling tools. Tubular housing 75 is provided with an outwardly extending annular bottom flange 76 and an outwardly extending top flange 77. A retaining ring 78 which bears on the top of bottom flange 76 and is secured in place by an annular series of bolts 79 rigidly holds housing 75 in axial alignment with openings 21 and 43.

The annular water course sealing disk, shown in perspective in Fig. 7 and numbered 80, is formed of soft pliable rubber and is supported in position above and spaced from opening 43 in the roof of the valve housing by means of a tubular retaining member 81 which rests on the housing roof 26 and is held in axial alignment with opening 43 by means of a centering flange 82 which projects upwardly from the upper surface of roof member 26.

The water course sealing disk is formed with an edge portion 83 which extends above and below the disk proper and forms a tubular rim therefor. The disk at its center is provided with a relatively small circular aperture or through opening 84 and is slit along radial lines which

extend from said opening to within a short distance of its tubular rim 83, thus forming a number of generally triangularly shaped pliable segments. Both upper and lower surfaces of these pliable segments taper from the outer solid portion of the disk portion indicated at 85 to its inner edge. These tapered flexible segments are easily stretched and deformed in an amount sufficient to permit passage of the drilling tools, and, because of the slotted construction, form a seal for the irregular portions of the drilling tools, especially those of the drilling jars and the water courses of the drilling bit.

Located above the water course sealing disk 15 are four other flexible sealing disks which are numbered 86, 87, 88 and 89. Disk 86 is spaced from and supported by a tubular member 90 and disks 87, 88 and 89 are spaced apart and supported by tubular members 91, 92 and 93. Disk 89 is held in place against the top of tubular support 93 and the requisite pressure for securely clamping this as well as disk 80 in place is secured by means of a tubular member 94 which is forced into position by an annular member 95 which forms the top of housing 75 and which is bolted to top flange 77 of said housing by a series of bolts 96.

Each of the disks 85, 86, 87 and 88 is provided with a peripheral edge flange similar to that of the water course sealing disk 80 and each is also molded from soft pliable rubber. Each of these disks is provided with a central aperture 97 which permits free passage therethrough of the drilling cable during its reciprocations. From this central aperture to its peripheral flange portion, each disk gradually increases in thickness and the under side of each disk is provided with a series of concentric grooves 98 as best shown in Fig. 6.

The texture of the rubber used in making these disks is such as to give to them sufficient strength to resist a considerable degree of deformation from the pressure of the oil and gas against them. The central apertures 97 are preferably all of the same size and are such as to permit the drilling string to be pulled therethrough without undue effort. At the same time, they are small enough to make tight contact with the drilling string to prevent the escape of oil and gas past the same. There being a number of these disks (the number may be varied if desired) it will be apparent that each acts as a stage in the reduction of pressure, so that there is but a relatively small pressure differential between their opposite sides and such pressure differential is not sufficient to break the contact between the disk and the drilling string as it passes therethrough.

The spacing of these disks is sufficient to prevent them from contacting with one another as they are deformed by the drilling string while being pulled therethrough. For this reason, the pressure differential is maintained even when they are thus deformed and there is no danger of bunching or wadding which might damage them and interfere with the normal passage therethrough of the drilling string.

The concentric grooves in their under faces add to the multi-stage sealing effect of packing device C during the period when the drilling string is being pulled therethrough; the disks at that time being flexed upwardly with their under surfaces in contact with the drilling tools. The spaced disks serve as an effective labyrinth packing device.

The packing device D for the drilling cable and which functions as an oil and gas saver is carried by annular member 95 which besides serving as the top of housing 75, serves as the supporting base for packing device D. The housing of packing device D is bilaterally symmetrical and longitudinally separable into two parts 99-99. These parts are carried on parallel hinge pins 100-100 which in turn are carried by mounting lugs 101 which project upwardly from base member 95.

The housing is provided with a central packing chamber having side walls 102-102 which in the main are parallel, and with aligned top and bottom openings for the drilling cable which are respectively numbered 103 and 104. These openings are in axial alignment with the central openings in the tool string sealing disks and the water course sealing disk.

A longitudinally separable, soft pliable rubber packing element is located within the packing chamber and each half thereof is numbered 105. This packing element is provided with a central circular cable channel 106 as well as a series of transverse slots 107 as shown by full lines in Figures 1, 2 and 4 and as indicated by dotted lines in Figure 5. The width of these transverse slots substantially equals the diameter of channel 106 and they do not extend for the full width of the packing element thus leaving the meeting edges of the halves unslotted. The depth of these slots, however, as will be seen, is greater than their width. Followers 108-108 for packing element halves 105-105 are movable to and held in adjusted position within the packing chamber by means of adjustment screws 109-109 which are threaded through end members 110-110 of the packing chamber. Each of these end members is secured in place by an upper bolt 111 and a lower bolt 112.

The side walls 102-102 of the packing chamber in the main are parallel but from points 113 the distance between such walls gradually decreases to points 114, and from this point to the longitudinal joint between the halves of the packing chamber the distance between said walls more or less abruptly decreases as shown in Fig. 5.

From this construction, it will be apparent that the longitudinally separable flexible packing can be adjusted for wear occasioned by the drilling cable by forcing the same inwardly toward the drilling cable. When this is done, the convergence of the walls causes the circular central channel 106 to close in to compensate for such wear.

Each housing half 99 is provided with a pair of outwardly extending arms 115 and a shaft or bar 116 passes through the outer ends of each pair of such arms. These arms are so formed and positioned that when the housing is closed as shown in Fig. 1, rods or bars 116 are located somewhat above hinge pins 100 and when the housing is open for the passage of drilling tools therethrough, they are located about the same distance below their hinge pins.

The outer ends of bars or rods 116 are connected by heavy tension springs 117.

Each arm 115 is provided with an operating bar socket 118 so that by placing an operating bar in either socket of one of said arms and then pulling outwardly on said bar, that half of the packing device having said arm in its make-up can be rotated about its hinge pin 100.

From the position of rods 116 with relation to hinge pins 100, it will be apparent that if either half of the oil and gas saver or packing device D 75

is swung outwardly about its hinge pin, the tension of springs 117 will reach their maximum when its rod 116, its hinge pin and the opposite rod or bar 116 are in line. As soon as rod or bar 116 passes below said line, the tension springs serve to pull such half to fully open position. The other half of the oil and gas saver housing will be pulled to open position by said springs when it is moved but a slight distance from closed position.

It will be apparent that it is easier to open one half of the oil and gas saver D at a time, but it will also be apparent that it is possible to manually open both halves simultaneously. When both halves are opened simultaneously as is done when opened automatically, the springs will be stressed to their maximum when both rods or bars 116 are in line with both hinge pins 100. When it is desired to close the device, the operation is reversed. The halves may be closed one at a time or simultaneously.

It will be noted that the spring arrangement and the location of bars or rods 116 with relation to the hinge pins 100 is such as to permit either or both halves to be in open or closed position and that when in such position they are under spring tension sufficient to hold them in such position; the springs being of sufficient strength so that considerable force is required to move the halves from either closed or open position.

The longitudinally separable housing for the oil and gas saver portion of the device is provided with a lower portion 119 which is provided with eyes 119a which embrace the hinge pin and with an annular bottom flange 120 which when the device is closed as in Figure 1, seats against the upper face of an upstanding flange 121 formed on base member 95. The upper face of flange 121 is provided with an annular groove within which a rubber sealing ring 122 is secured and which seals the joint between the lower face of flange 120 and the upper face of flange 121.

The inner surface 119b of member 119 is frusto-conical and the device being longitudinally separable, forms two actuating cams; one for each half of the housing whereby the cable socket as it is moved upward into contact therewith causes said halves to swing outwardly to open position about their hinge pins.

The oil and gas saver, or in other words, packing device D for the drilling cable, at its upper end is provided with a pair of guide spools or rollers 123-123 for centering and guiding the drilling cable. These spools are located on opposite sides of the joint between the housing halves 99-99 and are adjustable toward and from such joint for the purpose of accommodating drilling cables of different diameters.

Each of these spools or rollers, by means of spaced anti-friction bearings 124-124 is mounted on an eccentric cylindrical portion 125 of a mounting pin 126. Each of these pins extends through openings formed for its reception in the sides of the housing halves 99-99. The head 127 of each pin carries a locking member 128 which projects inwardly toward the housing and is adapted to be inserted within one of a series of spaced holes 129 drilled in one side of housing half 99 and arranged concentrically with relation to pin 126. End 130 of the pin is threaded to receive a nut 131 by means of which the pin is locked in adjusted position.

Operation

In operating the safety drilling-in head of

this invention, the shut-off valve A is closed and the oil and gas saver or packing device D for the drilling cable is opened. The drilling string is then lowered into the device until the drilling bit comes to a point slightly above valve disk

21. Operating lever 63 is then thrown so as to open the shut-off valve. The drilling string is then lowered until the rope socket is within the sealing device C for the drilling tools. One half of the oil and gas saver D is then closed and the drilling cable shifted to proper position with relation to roller 123 on the closed half of the oil and gas saver. After this, the other half of the oil and gas saver D is closed and the tools are lowered to the bottom of the hole.

It will be noted that during the time any part of the drilling string is within the drilling string sealing device C, pressure reduction sealing disks 85, 86, 87, 88 and 89 prevent the upward leakage of oil or gas around the string of tools, and, after the rope socket has been lowered into sealing device C and the oil and gas saver has been closed, leakage of oil and gas around the drilling cable or wire line during the drilling operation will be prevented.

When the tools are being withdrawn from the hole and the rope socket is drawn upwardly while in contact with the longitudinally separable frusto-conical inner surface 119b of member 119, both halves of the oil and gas saver D will be swung outwardly about their hinge pins until spring support bars 116 pass below said hinge pins, at which time springs 117 will cause said halves to fully open. It will be seen that opening of the oil and gas saver is accomplished automatically and while the oil and gas saver remains closed until lifted by the rope socket, opening of the same is accomplished at the proper instant. As soon as the drilling bit is raised above valve disk 21, operating lever 63 can be swung to position to close the valve. After the valve is closed, the tools can be pulled out of the safety drilling-in head.

From the above, it will be noted that by means of this safety drilling-in head, the flow of oil and gas is always under control and is at all times diverted from the working areas.

Having thus described our invention, what we claim as new and desire to secure by Letters Patent is:

1. In an oil and gas saver, a housing which is longitudinally separable into two parts and is provided with a packing chamber having aligned end openings, a longitudinally separable packing within said chamber, a support to which said housing parts are hinged, means yieldingly resisting the movement of said housing parts to open position when said housing is closed and to closed position when said housing is open, and drilling cable socket operated means for swinging the housing parts to open position.

2. In a drilling cable packing device, a longitudinally separable housing, a longitudinally separable packing within said housing, a support for said housing and to which its separable parts are independently hinged, and spring means yieldingly resisting the separation of said housing parts when the housing is closed and the closing of said housing when said parts are separated.

3. In a drilling cable packing device, a longitudinally separable housing, a longitudinally separable pliable packing element within said housing, a housing support, a hinge connection between each housing part and said support,

spring support arms extending outwardly in opposite directions from said housing, spring means connecting said arms above said hinge connections and cam means located on each housing part below said hinge connections.

4. In a drilling cable packing device, a longitudinally separable housing, a packing chamber within said housing and having aligned end openings, a flexible packing element within said 10 packing chamber and which is separable along the axis of said end openings, a plurality of guide spools adjacent one end of said housing, opposed cam surfaces adjacent the other end of said housing, a support to which the sections of said housing are hinged, spring support arms extending outwardly from opposite sides of said housing and spring means connecting said arms above the hinge connections between the housing sections and said support.

5. In a safety drilling-in head, a diversion chamber, a shut-off gate valve above said diversion chamber, a series of pliable drilling tool sealing disks arranged in axial alignment above said shut-off valve; one of said disks being radially slit into multiple sections and a longitudinally separable drilling cable packing above said drilling tool sealing disks and with its separable parts mounted for swinging movement beyond the path of travel of drilling tools traversing the 25 device.

6. In a drilling cable packing device, a pair of pliable packing elements provided with longitudinal grooves which together form a substantially cylindrical passage for a drilling cable, a housing for said elements, provided with longitudinally separable side walls which in the main are parallel but which converge adjacent their meeting edges, followers for said packing elements located between said side walls and means for 35 moving said followers toward one another whereby the free edges of said packing elements are forced inwardly by said converging side wall portions.

7. In a safety drilling-in head for use in drilling in oil and gas wells with cable tools, a diversion chamber provided with at least one side outlet, a shut-off gate valve above said chamber, means above said valve and which in cooperation with cable tools forms a labyrinth seal, and a longitudinally separable drilling cable packing 45 above said means and being so mounted that its parts can be swung to open position by the cable socket.

8. In a safety drilling-in head, a longitudinally separable drilling cable packing housing having aligned openings in its ends, a member to which the parts of said housing are independently hinged, cam elements adjacent one end of said housing and in the path of travel of the rope 55 socket, roller guides adjacent the other end of said housing and spring means tending to yieldingly resist separation of the housing parts when the housing is closed and closing of the housing when its parts are separated.

9. In an oil and gas saver, a housing which is longitudinally separable into two parts and which is provided with a packing chamber having aligned end openings, a longitudinally separable packing within said chamber, a support to which 60 said housing parts are hinged, arms extending outwardly from opposite sides of said housing, springs connecting said arms above the hinge points of the housing parts, rope socket operated means for swinging the housing parts to open 70

position and drilling cable guide rollers carried by said housing parts.

10. In an oil and gas saver, a housing, a packing chamber within said housing and which with said housing is longitudinally separable into two parts, a support to which said housing parts are hinged, a pair of arms extending outwardly from each housing part, a spring support connecting the outer end of each pair of arms, and spring means connecting said spring supports whereby said housing parts are yieldingly held in both closed and open positions.

11. In a shut-off valve device, a valve housing having aligned oppositely positioned openings, an annular member forming a valve seat extending into said housing through one of said openings and having an outwardly extending flange which underlies the housing around said opening, means located below said flange for yieldingly supporting said annular member, a valve member within said housing and slideable toward and from said seat, means for raising said valve member from said seat during movement thereof in one direction and means for forcing said valve member toward said seat during movements thereof in the opposite direction.

12. In a safety drilling-in head, a plurality of relatively soft pliable annular disks arranged in axial alignment and in superposed spaced rela-

tion, a sliding shut-off gate valve below the lowermost of said disks and a longitudinally separable drilling cable packing device above the topmost of said disks and which has its several parts mounted for swinging movement toward and from one another.

13. In a safety drilling-in head, a series of aligned relatively soft pliable annular disks each having one face thereof provided with concentric ridges and depressions, a relatively soft pliable packing disk axially aligned with said series and which is radially slit to provide a number of cooperating water course sealing segments, a shut-off valve below said radially slit disk and laterally adjustable guide rollers above the topmost disk of said series for holding the drilling cable in axial alignment with the disks of said series.

14. In a drilling cable packing device, a longitudinally separable housing, a longitudinally separable packing within said housing, a series of relatively soft pliable annular disks arranged in axial alignment and in superposed relation below said separable packing and a pair of laterally adjustable drilling cable guide rollers each carried by a part of said housing.
